CLAIM

The ornamental design for a wall mountable peg hanger, as shown and described.

DESCRIPTION

FIG. 1 is a perspective view showing the new design for a wall mountable peg hanger.

FIG. 2 is a front view thereof;

FIG. 3 is a right side view thereof, the left side view being a mirror image of the left side view shown;

FIG. 4 is a back view thereof; and,

FIG. 5 is a top view thereof; the bottom view being a mirror image of the tip view shown.
